UNITED STATES PATENT OFFICE.

WILLIAM H. SELLEW, OF DETROIT, AND EDWARD A. EVERETT, OF HIGHLAND PARK,
MICHIGAN.

INSULATED RAIL-JOINT.

1,022,884.

Specification of Letters Patent.

Patented Apr. 9, 1912.

Application filed November 15, 1909. Serial No. 528,261.

To all whom it may concern:

Be it known that we, WILLIAM H. SELLEW, a citizen of the United States, residing at Detroit, Wayne county, Michigan, and EDWARD A. EVERETT, a citizen of the United States, residing at Highland Park, in the county of Wayne, State of Michigan, have invented certain new and useful Improvements in Insulated Rail-Joints; and we do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an insulated rail joint for railway rails, and consists in the construction and arrangement of parts hereinafter more fully set forth and pointed out particularly in the claims.

The primary object of the invention is to provide simple and efficient means for electrically insulating the ends of railway rails to form electrically divided blocks, as in the block signal system.

A further object is to provide for joining the ends of the insulated rails in a manner to render the joints strong and durable and at the same time provide for electrically insulating the joined parts.

A further object is to so construct the joint that its parts may be readily assembled or connected and quickly and easily disconnected.

A further object is to so dispose the parts forming the joint that the strain of the passing train may be carried without causing the joint to sag or destroy the efficacy of the insulation between the joined parts.

A further object is to provide an insulated rail joint of such character that the parts of the joint bearing on the rail shall be of the same electric value as the rail itself, obviating the necessity of insulating said parts from the rail.

The above objects are attained by the structure illustrated in the accompanying drawings, in which:—

Figure 1 is an elevation of an insulated rail joint embodying our invention. Fig. 2 is a longitudinal section therethrough, as

on line 2—2 of Fig. 1. Fig. 3 is a view in perspective of two rail ends with the parts forming the joint mounted thereon but disconnected, the divided splice bars being shown bolted to the webs of the rails. Fig. 4 is a vertical longitudinal section through the projecting members on the meeting ends of the divided splice bar carrying the registering tenons and sockets through which pass the tapered tie bolts which receive the nuts adapted to screw onto said bolts and into said sockets, the parts being disassembled and the bolts appearing in elevation, the line of said section being indicated at 4—4 in Fig. 2. Fig. 5 is an inverted horizontal section through the two lower tie bolts and associated parts of the opposed splice bars, said section being taken on line 5—5 of Fig. 1, looking in the direction indicated by the arrows. Fig. 6 is an end elevation of one part of the divided splice bar, said part being the one carrying the tenons through which the tie bolts pass. Fig. 7 is a similar view of the opposite part of the divided splice bar, said part having the sockets which receive said tenons at one end, and into the opposite ends of which are screwed the nuts which engage said bolts. Fig. 8 is an elevation of an insulated joint, showing a slight modification of our invention. Fig. 9 is a horizontal section as on line 9—9 of Fig. 8. Fig. 10 is an elevation of the joint shown in Figs. 8 and 9 disconnected, showing in section a pair of the coupling members on one side thereof. Fig. 11 is a perspective view of the strip of insulation employed between the meeting ends of the parts of the splice bar.

In insulating rail joints where the continuous splice bars have been employed which cross the joint between the ends of the rails, it has been found difficult to maintain a perfect electrical insulation because of the necessity of insulating the lapping ends of the splice bars from the rails, which insulation is difficult to maintain in a perfect state, owing to the movement between said parts and the abrasive wear to which the insulation is necessarily subjected in such a structure. We overcome the objection incident to the continuous splice bar by dividing the splice bar which we employ transversely and electrically insulating

the joined ends thereof as well as the ends of the rails.

Referring to the characters of reference on the accompanying drawings wherein we have illustrated the preferred mode of applying our invention, 1 designates the railway rails, which may be of any suitable form, and the webs of which at their ends are apertured to receive the transverse bolts 10 that join the splice bars thereto. Instead of employing continuous splice bars in effecting our insulated joint, we make each bar in two parts, comprising the part 2 and the part 3 which are associated in pairs, and use 15 a pair of said parts upon each side of the rail joint. As the splice bars must be sufficiently strong to carry the weight of the train when crossing the joint between the rail ends, provision must be made where the 20 splice bars are divided transversely as in our structure for joining the parts thereof in a manner to render them sufficiently rigid to carry the necessary load, and at the same time afford means for effecting an electrical 25 insulation between the parts of the bar. This we accomplish by adding to the end of the part 2 of the splice bar, which is of the ordinary angular form in cross section, a lateral projection 4.

30 In one form of our invention, as shown in Figs. 1 to 7 inclusive, the vertical face of the projection 4 is provided with a tapered tenon 5, and formed through said projection and through said tenon is a tapered 35 aperture 6, as clearly shown in Fig. 4. Depending from the projecting portion 4 of the part 2 of the splice bar and formed integral therewith and integral with the base flange of said part 2 is a barrel-like member 40 7. This barrel-like member extends below the base 8 of the rail which lies in the opening 9 (see Fig. 6) between the base or bottom flange of the part 2 of the splice bar and said member 7. Projecting from the 45 inner end of the member 7 is a tapered tenon 10, and formed through member 7 and through said tenon is a tapered aperture 11. Passing through the tapered aperture 6 and extending from the tenon 5 is a tapered bolt 12, the taper of which coincides with the taper of the aperture 6 and which is provided at its projecting end with screw threads 13. Passing through the tapered aperture 11 and projecting from the tenon 50 10 is a tapered bolt 14, the taper of which coincides with the taper of said aperture 11 and which is provided at its projecting end with a screw thread 15, and at its opposite end with a head 16. The bolt 12 is insulated 55 from the wall of the tapered aperture through which it passes by means of a bushing 17 of mica, or other suitable insulating material. The bolt 14 is in like manner insulated from the wall of the aperture 11 60 by means of a similar bushing 18, the head 65

of said bolt being insulated from the head of the barrel-like member 7 by means of a suitable insulating washer 18a.

The part 3 of the splice bar is provided at its inner end with a lateral projection 19 corresponding with the projection 4 on the part 2, and said projection 19 is provided with an aperture 20 which is tapered for a portion of its length to receive the tenon 5, the remaining portion of said aperture 75 being threaded, as shown at 21, to receive the externally threaded nut 22 adapted to screw thereinto, said nut being internally threaded to screw onto the threaded bolt 12. From the projection 19 and the base 80 portion of the part 3 of the splice bar depends a barrel-like member 23 having an aperture 24 therethrough, which for a portion of its length is tapered to receive the tenon 10, the remaining portion of said aperture 85 being threaded, as at 25, to receive the externally threaded nut 26 adapted to screw thereinto, said nut being internally threaded to receive the threads of the bolt 14. In joining the parts of the splice bar, 90 the tenons 5 and 10 of part 2 are caused to enter the sockets 20 and 24 of part 3. Previous to joining said parts provision is made for insulating the meeting ends thereof by placing between said ends a layer or filling 95 strip 27 of insulating material which is cut to conform to the shape of the meeting ends of the splice bar parts and is apertured to permit of the passage of the tenons 5 and 10 therethrough. When the parts of the 100 splice bar have been placed with their ends together and with the tenons of one part in the sockets of the other part as described, said parts are rigidly coupled by passing the tapered bolts 12 and 14 through the tapered apertures 6 and 11 and screwing onto the ends of said bolts the nuts 22 and 26 respectively, said nuts being externally threaded to receive the threads in said sockets. If desired, the threads upon the interior and exterior of said nuts may be of different trend so as to cause the bolts to be drawn tightly into their respective apertures in advance of the seating of said nuts in the tapped sockets into which they are 110 screwed, thereby providing for the placing of a proper tension upon the bolts to draw the parts firmly together, and at the same time serving to lock the nuts against becoming accidentally unscrewed. When the 115 parts of the splice bar shall have become joined, as above described, said parts will be perfectly insulated by the filling strip 27 of insulating material between the ends thereof, by the bushings of insulating material in the tapered apertures around the tapered tie bolts and by the sleeves 28 of insulating material around the tenons 5 and 10 which are placed on said tenons before 120 they are entered in the sockets 20 and 24, or 130

which may be placed in said sockets as bushings before the tenons are entered. By this arrangement the complementary parts 2 and 3 of the splice bar are insulated electrically 5 from each other and yet are so firmly coupled as to effect a rigid union between the joined parts, rendering the bar equal in strength and rigidity to the continuous bar commonly employed.

- 10 The part 2 of the splice bar is apertured to receive the transverse bolts which join the bars to the ends of the rail. The part 3 of the splice bar is provided with an integral bolt 29 projecting from the inner 15 face thereof, as shown in Fig. 7, adapted to pass through the end of the rail and through the part 2 of the opposite splice bar. It is necessary to form this bolt integral with the part 3 for the reason that the presence 20 of the lateral projection 19 prevents the passage of a separate bolt through the splice bar part at that point. The outer ends of the splice bars are joined to the web of the rail by the transverse bolts 30.
- 25 In connecting the rails to effect an insulation of the joint in accordance with our invention, the abutting ends of the rails are electrically insulated by placing therebetween a dividing layer or strip 31 of insulating 30 material which is of the same shape in cross section as the rail; the ends of the rails are then connected by means of the two part splice bars which are bolted thereto by the transverse bolts 29 and 30, as in ordinary 35 practice. By this arrangement the ends of the rails are rigidly coupled together and are at the same time perfectly insulated electrically from each other, the arrangement being such that the parts of the splice bars 40 or coupling members which are fastened to the ends of the rails are of the same electric value as the rails themselves, obviating the necessity of placing insulating material between the splice bars and the rails where 45 the rubbing or abrasive action incident to the movement between said parts soon destroys said insulation, and renders the joint ineffective in arresting the flow of an electric current carried by the rails.
- 50 Notwithstanding the fact that the splice bars which we have shown herein are divided transversely, the manner of connecting them, as shown herein, renders said bars sufficiently rigid to firmly support the joint 55 between the rail ends. The lower bolts 14 crossing between the depending parts 7 and 23 below the longitudinal axis of the rails and tying said members together, serve as the tension members of a truss formation.
- 60 It will further be understood that because of the long bearings afforded by reason of the tapered tenons of one part of the splice bars entering the correspondingly shaped sockets in the other part, and the further 65 fact that said parts are connected by two ty-

ing bolts which cross the probable line of rupture in separate planes, all movement between the joined parts of the splice bars is obviated, thereby entirely overcoming any liability of injury to the insulation which is 70 employed to electrically separate said parts.

The heads 16 upon the lower bolts 14 employed in the structure shown in Figs. 1 to 7 inclusive, prevent the possibility of said bolts being drawn too far into the tapered 75 apertures 11 by the strain to which they are subjected, obviating a possible loosening of the joint through that cause. It is only necessary to unscrew the nuts from the transverse bolts 29 and 30 to enable the splice 80 bars to be removed from the rails whenever desired, an arrangement which makes it unnecessary to disturb the joint between the connected parts of said bars after they have been coupled together. It will be 85 noted that the insulated joint between the ends of the rails is coincident with the insulated joint between the connected parts of the splice bars when said bars are secured to the rails, as shown in Figs. 1 and 2, 90 thereby making effective the electrical separation between the ends of the rails.

In Figs. 8 to 10 inclusive, the tenons shown in the other views through which the tie bolts pass, are omitted, and said bolts are formed integral with the lateral projection 4 on the part 2 of the splice bar, while the tapered sockets in the part 3 are of a diameter to snugly receive said bolts within the insulated bushings 32 therein, the bolts passing entirely through said sockets and receiving upon their threaded ends the nuts 33, there being a washer 34 of insulating material around each of said bolts against which said nuts are turned. The construction shown in Figs. 8 to 10 inclusive is simpler than that shown in the other views and may be found more desirable because of the lesser number of parts; the principle, however, is the same as that of the previously 95 described construction, differing only therefrom in the physical embodiment of said 100 principle.

We have shown what seems to be the preferred form of embodying our invention, 115 but do not wish to be limited to the specific mechanical arrangements illustrated herein, as other forms of embodying our invention may be employed, without departing from the spirit thereof.

Having thus fully set forth our invention, what we claim as new and desire to secure by Letters Patent, is:—

1. An insulated splice bar for insulating rail joints, comprising two parts, one part 125 having tapered tie-bolts, the other part having tapered sockets to receive said bolts and provided with threaded apertures communicating with said sockets, externally and internally threaded nuts screwing onto said 130

- bolts and into said sockets, and insulating material between the parts of said splice bars, and between the connecting members thereof to electrically insulate one part from the other. 5
2. An insulated splice bar for insulating rail joints, comprising two parts, one of which is provided with tenons and with apertures passing through said tenons, the other 10 part being provided with sockets to receive said tenons and with threaded apertures communicating with said sockets, bolts passing through said tenons and through said sockets and apertures, externally and internally threaded nuts screwing onto said bolts and into said sockets, and insulating material between the parts of said splice bar and between the connecting members thereof to electrically insulate one part from the other. 15
- 20 3. An insulated splice bar for insulating rail joints, comprising two parts, one part having tapered tie-bolts formed integral therewith, the other part having tapered sockets to receive said bolts which are disposed in substantially vertical alinement with the lower bolts under the base of the rail, insulating material between the parts of the bar and between the bolts and their receiving sockets, and nuts engaging said 25 bolts for drawing the parts of the bar together. 30
4. An insulated splice bar for insulating rail joints, comprising two parts, one of which is provided with tapered tenons and with apertures passing through said tenons, the other part being provided with tapered sockets to receive said tenons and with threaded apertures communicating with said sockets, bolts passing through said tenons and through said sockets and apertures, externally and internally threaded nuts screwing onto said bolts and into said sockets, and insulating material between the parts of said splice bar and between the connecting members thereof to electrically insulate one part from the other. 45
5. In an insulated rail joint, the rails, separate splice bar sections for each rail, one of the adjoining bar sections having 50 projecting tie bolts formed integral there-
- with, the other adjoining bar section having sockets to receive said bolts which are disposed in substantially vertical alinement with the lower bolts under the base of the rail, nuts upon the ends of said bolts for drawing the adjoining splice bar sections together, a transverse bolt projecting from one splice bar section passing through the rail end and through the splice bar on the opposite side of the rail, and insulating means between said connected parts. 55
6. In an insulated rail joint, the rails, separate splice bar sections for each rail, the adjoining sections having lateral projections above the base of the rail and barrel-like members formed integral with said projections depending below the bottoms of the rails, bolted couplings between said projections and between said barrel-like members, an integral transverse bolt 70 extending from one of each pair of the adjoining splice bar sections through the end of the rail and engaging the splice bar section on the opposite side thereof, and insulating means between said parts. 75
7. In an insulated rail joint, the rails, separate splice bar sections for each rail, the adjoining bar sections having coinciding lateral projections above the rail base, longitudinal tie bolts joining said projections, integral members on said lateral projections of said splice bar sections embracing the base of the rails and depending below the bottoms thereof in a truss formation, a tension member passing through the members 85 of the truss, means for placing stress upon said tension member, transverse tie bolts connecting the opposite splice bar sections through the rail ends, said bolts being integral with and extending from said lateral 90 projections in the plane thereof, and means for insulating said parts. 80
